RAILROAD SPREADER

James C. Forbes and Steven Krusich, East Chicago, Ind., assignors to O. F. Jordan Company, East Chicago, Ind., a corporation of Indiana

Application May 19, 1934, Serial No. 726,464

13 Claims. (Cl. 104—1)

This invention relates to improvements in railroad spreaders and it consists of the matters hereinafter described and more particularly pointed out in the appended claims.

5 The rails in track, even on different branches of the same railroad, often vary in height from a minimum of about $4\frac{1}{2}$ " to a maximum of about 7".

In railroad spreaders having a vertical adjustable front plow as heretofore made, the lowest limit to which the plow could be adjusted with respect to the ties, was about $2\frac{1}{2}$ " below the top of the rail. This amount of movement was limited by the rail shoe which is associated with the 15 rail opening in the cutter shoe, carried by the plow.

It is desired in passing over new ballast deposited in track, to bring the plow as close as possible to the top of the ties, as this eliminates 20 much shoveling work. It is apparent that in spreading ballast in a track where high rails are employed, when the plow could be adjusted to only $2\frac{1}{2}$ " below the top of the rail, a considerable body of ballast was left in track and required hand removal, which it is desired to avoid.

One of the objects of the present invention is to provide a cutter shoe and rail shoe arrangement in a railroad spreader, wherein a range of adjustment is provided between the said shoes, to 30 accommodate close working of the plow with respect to the ties, regardless of the height of rail found in track.

Another object of the invention is to provide a cutter and rail shoe structure wherein the rail shoe may be quickly and easily adjusted vertically of the cutter shoe.

Still another object of the invention is to provide a structure of this kind where the cutter shoe and the rail shoe have interengaging parts, 40 so that the rail shoe may be removed horizontally forward from one position on the cutter shoes, and replaced in an opposite manner in either a higher or lower position and then securely locked in the new position, the said interengaging parts 45 amply resisting the upward thrust met with in use.

The above mentioned objects of the invention, as well as others, together with the many advantages thereof, will more fully appear as we 50 proceed with our specification.

In the drawings:

Fig. 1 is a fragmentary view in front elevation of the front plow of a railroad spreader embodying our improved cutter and rail shoe construction and shows the plow in its lowermost position

to bring the cutter shoe into its lowest working position.

Fig. 2 is a view similar to Fig. 1 with the cutter and rail shoes in a different position.

Fig. 3 is a horizontal detail sectional view on an enlarged scale through a part of the improved shoe structure as taken on the line 3—3 of Fig. 1.

Fig. 4 is a vertical detail sectional view through the improved shoe structure as taken on the line 10 4—4 of Fig. 3.

Fig. 5 is a fragmentary view in front elevation on an enlarged scale of a part of the rail shoe and associated part of the cutter shoe, showing a further changed position of the rail shoe with 15 respect to the cutter shoe.

In general, the invention as shown herein includes a front plow so mounted with respect to the spreader as a whole, as to be movable from a position wherein the plow cutter shoe is above 20 the rail tops for transport purpose, to one wherein the plow cutter shoe is in that lowered position which spreads and evens the new ballast to the desired level. The plow and its cutter shoes are V-shaped in plan and as the 25 spreader progresses along the track, the cutter shoe operates to even the ballast to the desired level. The divergence of the sections of the plow, naturally causes a movement of the excess ballast between rails, laterally and over the rails with 30 a wave action, onto the tie ends. To keep the rails clean for movement of the spreader as a whole, upon the rails, there are mounted on the cutter shoe one above each rail, an auxiliary shoe that may be adjusted with respect to the top of 35 the rail to clean the rail tops of the ballast piled upon them. This last mentioned shoe is termed a "rail" shoe to distinguish it from the "cutter" shoe upon which it is mounted.

The structure while described as used in connection with ballast spreading operation, is also useful in snow and ice removal, so that of course, it is not desired to limit the structure to one for ballast use only.

Referring now in detail to that embodiment of 45 the invention, illustrated in the accompanying drawings:

1 indicates, as a whole, the front plow of a railroad spreader which may be mounted with respect to the front end structure 2 of the spreader 50 as to be adjusted vertically of the same, to an extent substantially equaling the highest rail found in railroad practice. The plow consists of a pair of laterally and rearwardly diverging plow sections 3 and secured to bottom end of the front 55

face of each section is a cutter shoe section 4. Preferably the cutter shoe section has a bolted-on, removable connection with its associated plow section.

5 At a point above each rail, the associated cutter shoe is provided with a downwardly facing, rail accommodating recess 5. Spaced laterally from each side of said recess is a vertical row of apertured ears 6, separated by spaces 7. That 10 part of the cutter shoe between said rows of ears provides a way 8 (see Fig. 2) to receive a rail shoe 9.

Each rail shoe which is substantially in the form of a plate, includes a body 10, provided at 15 each side with a vertical row of apertured ears 11 separated by spaces 12. The ears of the two shoes are so proportioned that they fit in the spaces 7 between the ears 6 of the associated cutter shoe and the ears of the latter fit in the 20 spaces 12 between the ears on the rail shoe.

When a rail shoe is in position in its way on the cutter shoe, a pin 13 may be inserted through the ears of the cutter and rail shoes to secure the rail shoe in position.

25 Each rail shoe is provided at the bottom on its front side with a plow-like projection 14 and is also provided at the bottom on its rear side with a horizontal extension 15. The front end of the bottom surface of the projection 14 is curved upwardly better to engage the top of a rail and push off such material as may be upon the same. The extension is so proportioned in width with 30 respect to the sides of the associated rail recess 5 as to limit the uppermost position of the rail shoe in its way. Thus when the said projection 35 engages the top of the associated recess, it is assured that the top edge of the rail shoe cannot project above the top edge of the cutter shoe.

The bottom portion of each cutter shoe, inwardly of the associated rail accommodating recess is turned forwardly as a blunt cutting edge 16. The said bottom portion of each cutter shoe outwardly of the said recess is provided with an outside or tie end cutting shoe 17. This tie 45 end cutting shoe is preferably made as a separate element to have a bolted-on removable attachment to the cutter shoe 4.

Assume that it is desired to position the cutter shoe edge 16 as close as possible to the ties of the 50 track. The pins 13 are removed from the interengaged ears 6 and 11 and the rail shoes are removed in a forwardly direction. The plow 1 may now be lowered to bring the edge 16 of the cutter shoe into the desired working position with 55 respect to the ties. After the cutter bars have been thus positioned, the rail shoes are replaced with the ears 11 disposed in those spaces 7 between the cutter shoe ears, as will bring the bottom surface of each rail shoe in a position 60 closely adjacent the top of the associated rail. The pins 13 are then replaced and this locks the rail shoe in place.

65 Due to the upward curvature of the front end of the bottom surface of each rail shoe, it is apparent that such ballast material that flows over the associated rail as the spreader moves forward, will tend to exert a heavy upward pressure on the rail shoe. Because of the interengaging and ear arrangement between the cutter shoes and rail shoe, the upward lift or pressure on the rail 70 shoe is amply resisted by a wide distribution of pressure through said ears so that no single ear is required to withstand the pressure exerted.

75 By the arrangement described, the rail shoes may be quickly adjusted to accommodate that

position of the cutter shoe at which it is desired to work. Furthermore by means of the structure described, it is possible to accommodate a wider range of adjustment of the cutter shoe.

When the spreader is in transport from one 5 place of use to another, the plow is elevated to that position wherein the edge 16 of its cutter shoes clears the top of the rails. To give a maximum of clearance above the rails, the rail shoe may be removed and then replaced in its 10 topmost position wherein the top edge of the rail shoe is substantially flush with the top of the cutter shoe.

By reason of the structure described, whereby the rail shoe is removed forwardly for adjustment, it is impossible for such material as may accumulate back of the rail shoe, operating to bind or jam the shoe in a manner preventing the easy adjustment of the rail shoe. This is apparent because the removal of the rail shoe for 20 adjustment will dislodge such material as may have accumulated behind the rail shoe.

The construction described may be easily manufactured at low cost. It is simple to operate for its intended purpose and permits of an adjustment of the cutter shoe into all desired working positions.

While in describing the invention, we have referred in detail to the form, arrangement and construction of the parts thereof, the same is not 30 to be considered by way of limitation as said form, arrangement and construction may vary without departing from the spirit of the invention.

Furthermore, while in describing the invention, we have set forth its use in ballast spreading operations, we do not wish to limit ourselves thereto as it may also be used for the removal of snow and ice from between and from on the 40 top of the rails.

We claim as our invention:

1. In a railroad spreader, a front plow, shoes, one for each rail of the track, and means for mounting said shoes for vertical adjustment on said plow toward and away from the associated 45 rail.

2. In a railroad spreader, a front plow, shoes, one for each rail of the track, means enabling removal of the shoes from the plow in a direction parallel with the rail and replacement there- 50 of in a similar direction at a different elevation on the plow.

3. In a railroad spreader, a front plow, shoes, one for each rail of the track, means enabling removal of each shoe from one position on the 55 plow in a forward direction and its replacement in another position on the plow in a rearward direction.

4. In a railroad spreader, a front plow, shoes, one for each rail of the track, means enabling 60 removal of each shoe from one position on the plow in a forward direction and its replacement in another position on the plow in a rearward direction, and means for securing the shoe against accidental displacement from the last mentioned 65 position.

5. In a railroad spreader, a front plow, a cutter shoe thereon, other shoes, one for each rail mounted on the cutter shoe for movement toward 70 and away from an associated rail.

6. In a railroad spreader, a front plow, a cutter shoe thereon, other shoes, one for each rail, a guideway on the cutter shoe for an associated rail shoe, and means whereby the said shoe may 75

- be arranged in different adjusted positions in said guideway.
7. In a railroad spreader, a front plow, cutter shoes thereon, other shoes, one for each rail, and means on the side portions of each rail shoe and on the cutter shoe respectively, providing for a guided adjustment of the rail shoes on the cutter shoe. 5
8. In a railroad spreader, a front plow, cutter shoes thereon, rail shoes and interengageable parts on the side portions of said rail shoes and on the cutter shoes respectively, whereby the rail shoes may be engaged at the desired elevation on the cutter shoes. 10
9. In a railroad spreader, a front plow, cutter shoes thereon, a plurality of sets of vertically aligned ears on said cutter shoes with spaces between the ears, and a rail shoe having ears at each side thereof adapted to be engaged in the spaces between the ears of the cutter shoes to position the rail shoe at the desired elevation on the cutter shoe. 15
10. In a railroad spreader, a front plow, cutter shoes thereon, a plurality of sets of vertically aligned ears on said cutter shoes with spaces between the ears, a rail shoe having ears at each 20
- side thereof adapted to be engaged in the spaces between the ears of the cutter shoes to position the rail shoe at the desired elevation on the cutter shoe, and means inserted through said ears to prevent displacement of the rail shoes. 5
11. In a railroad spreader, a front plow, a rail shoe mounted for vertical adjustment thereon and having a forwardly extending lip at the bottom formed with an upwardly and forwardly curved bottom surface. 10
12. In a railroad spreader, a front plow, having a recess therein, a rail shoe mounted for vertical adjustment on the plow forwardly of said recess, said shoe having a forwardly extending lip and a rear extension portion arranged in the plane 15 of the recess, the bottom of said lip being formed into an upwardly and forwardly curved bottom surface.
13. A rail shoe for a railroad spreader comprising a plate-like body member having a plurality of vertically spaced ears along each side and having a forwardly projecting portion at the front bottom portion provided with bottom surface that extends upwardly and forwardly. 20
